UNITED STATES PATENT OFFICE.

THOMAS E. ADAMS, OF CLEVELAND, OHIO.

HOIST.

Application filed June 20, 1923. Serial No. 646,511.

To all whom it may concern:

Be it known that I, THOMAS E. ADAMS, a citizen of the United States, residing at Cleveland, in the county of Cuyahoga and

5 State of Ohio, have invented a certain new and useful Improvement in Hoists, of which the following is a full, clear, and exact description, reference being had to the accompanying drawings.

10 My invention relates to hoisting machinery, and in particular to a portable electric hoist, although certain of its features are of more general application as will herein-after appear.

15 In fact, the fundamental thought which constitutes the essence of my invention and the nucleus of the improvements and developments herein disclosed, is that of providing an internal worm gear and a worm

20 cooperating therewith the axis of which is in substantially the central plane of the wheel; and the wide range of utility of an arrangement of this kind is self-evident. As to this basic thought, the objects in view

25 are to greatly increase the efficiency and holding power of worm gearing; to render the same more compact; to improve the lubricating facilities of such gearing; and to provide an arrangement which adapts 30 itself more readily to certain circumstances, and to a greater number of uses, than prior forms of worm gearing.

That the nature of my invention as it pertains to improvements in portable hoists 35 may be better understood and its advantages more fully appreciated, brief reference may be made to prevailing types of portable hoists by way of comparison. For example, one object of my invention is compactness, 40 and another is lightness, where as little has heretofore been accomplished in these directions in the designing of hoists of the class to which my invention particularly relates.

Another object is to provide a hoist that 45 will sustain any load within the range of its lifting capacity with absolute certainty without the aid of a brake. In the case of my improved hoist a brake is employed only for the purpose of obtaining accuracy in the

50 stopping of a load in suspension.

Another object of my invention is to provide a unique gear arrangement characterized by two sets of worm gears in series which effects the highly desirable gear reduction and increased power without the objectionable number of gears usually em-

ployed in the attainment of these ends. This feature contributes to the compactness and lightness of the structure and is responsible for the positiveness with which the 60 hoist sustains its load. As will be gathered from this, this gear arrangement is especially suitable for the purpose at hand, although its adaptability to other uses will be apparent.

Further objects of the invention are to provide a hoist of the aforesaid character that is very powerful for one of its size and weight, and is substantial and durable; to provide a portable hoist that may be readily 70 handled by one man in that by engaging the lifting cable to a support in the vicinity of the one from which it is desired to suspend the hoist, the hoist may be operated to cause it to climb the cable so that all the 75 operator need do after it has attained the desired elevation is to engage its suspension hook with the trolley or other support from which the hoist is to be hung; to provide for various cable and pulley arrangements 80 whereby the hoist may be caused to lift light loads quickly and heavier loads more slowly with a proportional increase of power; to provide an electric hoist that will safely hold its maximum load whenever the electric power ceases; to provide means for stopping the hoist automatically when the load 85 has reached a given elevation thereby to prevent damage should the operator through any cause fail to shut off the power; and to 90 provide an electric hoist wherein, by the use of a single element or cable, the operator may start, stop or reverse the motor, or apply the brake for effecting an accurate stop.

The foregoing objects, with others herein- 95 after appearing, are attained in the embodiments of the invention illustrated in the accompanying drawings wherein Fig. 1 is a side elevation of my improved portable electric hoist with a part of the casing broken 100 away to reveal certain structural features; Fig. 2 is a perspective view of the control element or cable; Fig. 3 shows, more or less diagrammatically, the manner of elevating the hoist to position for use; Fig. 4 is a 105 central vertical section through the hoist at right angles to the plane of Fig. 1 and on a scale considerably enlarged over that of Fig. 1; Fig. 5 is an enlarged sectional detail of the combined worm and worm wheel and 110 its mounting; Fig. 6 is a sectional detail, substantially on the line 6-6 of Fig. 4,

showing the brake; Fig. 7 is a detail of the means for automatically opening the circuit when the load attains a given elevation; and Figs. 8 and 9 are a side elevation and 5 a vertical sectional view, respectively, of a manually operated hoist incorporating the internal worm gear of my invention.

Describing first the embodiment illustrated in Figs. 1 to 7, the motor casing, 10 which is substantially spherical, is comprised of upper and lower sections 1 and 2, respectively. The motor is preferably of the three-phase induction type. The laminated stator 3 is supported in a plane transverse 15 the inclined axis of the casing, and the edges of the casing sections come together about the stator. The primary winding 4 is suitably engaged within slots or grooves of the stator; while the secondary "winding," so-called, 20 is made up of conductor rods 5 which extend through the laminations of the rotor 6 and are connected at their ends to the end rings 7 and 8. The latter ring 8 (Fig. 4) instead of being flat, as usual, is cylindrical so as to serve as a brake drum, as will presently appear. From this brief 25 description of the rotor it will be recognized as one of the well known squirrel-cage type. While on this point it may be explained 30 that end ring 7 might also be made cylindrical and have associated with it a magnetic brake which, according to common practice, is automatically set by a spring, when the current to the motor is shut off, 35 and maintained in ineffective condition as long as the current flows; it being remembered that in brakes of this character the windings of the brake mechanism and motor are in series. Illustration of this is deemed 40 unnecessary as it would require only the changing of ring 7 to a form substantially like that of ring 8 and the supplying of the well known magnetic brake mechanism.

The rotor is clamped between flanges 45 and 11 upon the motor shaft 12, the flange 10 engaging an abutment 13 on the shaft, while a nut 14, that is applied to a threaded portion of the shaft, engages the flange 10. The respective upper and lower ends of the 50 shaft 12 are journaled within suitable anti-friction bearings 16 and 17 which are contained within cavities formed in the casing sections, the cavity which houses the bearing 16 being closed by a cap 18 containing a washer 19 of suitable packing material so that lubricant supplied to the bearing 16 will not find its way to the electrical elements of the motor.

A suitable distance below the stator, the 60 casing is divided by a partition 25 having a central aperture through which the lower end of the motor shaft extends, and the partition incorporates a housing 26 within which an anti-friction bearing 27 is contained which serves to support the motor

shaft intermediate its ends. In a reduced annular portion of the housing 26 is contained a washer 28 of packing material which prevents lubricant, present in the compartment below the partition 25, from 70 passing from the under to the over side of the partition should the hoist be inverted during handling.

A worm 30 is secured to the lower end of the motor shaft and meshes with a worm 75 gear 31 that is formed about the waist or equator of what I shall term a combined worm and worm gear 32, the end portions whereof are provided with threads. This combined worm and worm gear is, in effect, 80 a worm having the central portion of its thread interrupted, the lead of the threads at the two ends being one and the same, and therefore, in effect, continuous.

A hoisting drum 35, shown as provided 85 with the usual cable groove, surrounds the motor casing and is supported therefrom through ball bearings 37 which operate between inner and outer races 38 and 39, respectively, the former being fitted to annular shoulders 40 of the motor casing, and the latter having their peripheral portions threaded and screwed into the internally threaded edge portions of the drum 35. 90 Near their inner edges, and on their inner sides, the ball races 39 are grooved to receive expanding spring rings 41 which constitute abutments for the inner edges of the inner ball races. Preferably the ball races 95 are stamped from sheet metal of suitable gauge and quality, such a method of production insuring accuracy and uniformity, as well as cheapness. Rings 42, of suitable packing material, are interposed between the inner edge portions of the outer ball 100 races and the adjacent portions of the motor casing for the purpose of excluding dust from, and retaining lubricant within, the casing.

An internal worm gear 45 extends about 105 the interior of the drum 35 and is preferably formed integral therewith, and the teeth of said worm gear mesh with the threaded portions 32 of the combined worm and worm gear 31. The lower casing section 2 is provided with brackets 46 (Figs. 1 and 5) which overhang the worm gear 110 45 and support a stub shaft 47 whereon the combined worm and worm gear 31 is mounted through anti-friction bearings 48. Suitable means, such as a cotter pin 49, extending through registering holes in one of 115 the brackets 46 and the shaft 47 and serves to retain the shaft against longitudinal displacement.

Frames 50 are disposed on opposite sides 120 of the motor casing and are secured thereto by bolts 51 and 52 which pass through the casing and through portions of said frames. The frames are further secured to the motor 125

casing by bolts 53 which assist in securing the sections 1 and 2 of the motor casing together. To lugs 55 of the frames 50 are pivotally connected the ends of a yoke 56 which 5 has swiveled to it the suspension hook 57 by means of which the hoist is hung from a suitable sustaining structure. A loop 60 is pivotally connected at 61 to extension 62 of the frames 50, and a hook 63, that is secured 10 to one end of a hoisting cable 64, is engaged with the loop 60. The other end of the cable 64 is fastened at 65 to the drum 35. The cable is adapted to wind upon the drum and follow the spiral groove thereof in the usual 15 manner, and suspended upon the cable is a sheave block 67, equipped with a lifting hook or grapple (not shown).

Obviously, in lieu of the cable arrangement just described, a second sheave block may be 20 hung from the loop 60, and the cable 64 engaged over it and the hook 63 suitably connected to the sheave block 67, thus decreasing the speed with which the load would be lifted when the motor is running at a given 25 speed, while proportionately increasing the power. Or, a double sheave block could be substituted for the sheave block 67, and a single sheave block suspended from the loop 60, with an appropriate arrangement of the 30 cable 64, which would further increase the lifting power of the hoist. Thus, by using multiple sheave blocks, the power may be increased to whatever is desired. The obviousness of these arrangements make specific illustration unnecessary.

An expanding non-magnetic brake shoe 70 (Fig. 6) is located within the end ring 80 which, as previously stated, constitutes a 40 brake drum. To the inner side of the central portion of the shoe is attached a bifurcated fitting 71 which embraces a stub 72 that is secured to and rises from the partition 25 (Fig. 4). A spring 73, which has its ends connected, through fittings 74, with the 45 ends of the brake shoe, tends to contract the shoe and engage opposed abutments 75, shown as formed integral with the fittings 74, with the opposite sides of a cam 76 that is mounted upon a stud 77. An arm 78, which 50 is fixed with respect to the cam 76, has its free end pivotally connected to one end of a link 79, the other end of the link being similarly connected at 80 to a lever 81 that is pivoted at 82 to the motor casing. A spring 55 85 tends to maintain the lever normally in close proximity with the casing. The free end of the lever 81 is shown as provided with an eye 86 for the connection, as through a snap 87, of a brake control element or cable 88.

Within a hollow boss 90 that is formed in one side of the upper section 1 of the motor casing are supported contact posts 91, which have connection, through the leads 92, with 60 certain sections of the primary winding 4,

in accordance with usual construction of three-phase induction motors. The posts 91 are preferably supported upon and insulated from a substantial stool 94, the legs 95 whereof extend out over the adjacent portion of the winding 4 and are secured to the stator 3. A plug 96 is designed to fit within the boss 90 and contains sockets 97 for the reception of the contact posts 91.

The plug 96 may be fitted into the boss 90 75 in either of two positions which are 90° apart. When the plug 96 occupies one of its two angular positions within the boss 90, connections are established which will cause the motor to run in a given direction; but when the plug is inserted into the boss 90 in its other position it will establish connections causing the motor to run in a reverse direction. This will be readily understood 80 by those familiar with the type of motor in question, and the arrangement of contacts is a matter of electrical expediency.

In Fig. 3 I have shown more or less diagrammatically a track 100 on which a trolley 101 is mounted. The trolley may be 90 shifted to any position along the track, but at all times maintains electrical contact, through shoes or brushes shown conventionally at 102, with electrical conductors 103. A connection similar to that just described 95 as comprised, generally, of the posts 91 and sockets 97 occurs at 104 on the trolley 101. 105 indicates a cord or cable containing electric wires or conductors through which electrical connection is made between the trolley 100 and the motor.

This cord or cable terminates at one end in branches 106 and 107 (Fig. 2) the former having connection with the block 96, and the latter with a block 108 which constitutes a 105 part of the previously mentioned connection 104 of the trolley 101. The opposite end of the cord or cable 105 has branches 110 and 111 which carry, respectively, a socket member 112 and a plug member 113, of a separable switch. For convenience and the avoidance of confusion when operating the hoist, the brake control cord or cable 88 may be incorporated in the cord or cable 105.

When the hoist is suspended from the 115 trolley 101 and is in readiness for use, the plug 108 is inserted in the trolley connection 104 and the plug 96 inserted in the boss 90 of the motor casing. Now, when it is desired to lift a load, the lifting hook or 120 grapple is engaged with the load and the plug member 113 is inserted within the socket member 112 of the separable switch with the indications 112^a and 113^a of the respective members 112 and 113 opposite each 125 other. Current will be directed through the motor to cause it to rotate the drum in a direction to lift the load. As soon as the switch members 112 and 113 are separated, the load will be stopped. To prevent mo- 130

- mentum of the moving parts from causing the load to travel further than is intended, the cord or cable 105 may be pulled to set the brake shoe 70 against the ring or drum 8 and positively stop the parts. To reverse the motor, the switch members 112 and 113 may be brought together in a position reverse to that wherein the indications 112 and 113^a are in register.
- 10 To guard against damage which would occur should the operator through carelessness or other cause fail to open the switch when hoisting a load, I provide the following mechanism: 115 is a stub shaft journaled within a boss 116 that is formed on the motor casing, and to one end of the shaft is secured a lifter 117 while an arm 118 is fastened to the other end thereof. The free end of the arm 118 is so disposed to the edge 20 of the drum 35 as to be engaged and depressed by the cable 64 when the latter arrives at the adjacent edge of the drum. The free end of the lifter 117 normally reposes beneath one end of an elongated head 120 25 wherewith the plug 96 is equipped, the opposite end of said head extending over a rib 121 that is formed on the adjacent frame 50. Consequently, when the load has been elevated a distance determined by the entrance of the cable 64 into the last convolution of the drum 35, the arm 118 will be depressed by the cable thereby to elevate the lifter 117 and kick the plug 96 out of the boss 90 and open the circuit, the head 120 30 of the plug rocking upon the rib 121 during the operation. The load will then be held suspended, without danger of coasting due to the effective locking of the worm gears, until the operator again inserts the 35 plug 96 within the boss 90. When this is attempted, he is restrained, by the elevated condition of the lifter 117, from placing the plug in its former position and is compelled to insert it in its other position which will 40 result in reversing the motor and lowering the load.
- 45 A convenient method of elevating the hoist to its suspended position is illustrated in Fig. 3. The cable 64 may be run off the drum 35 and carried up a ladder 125 and engaged about a support, such as a beam 126. The plug 108 is inserted in the trolley connection 104, while the switch member 112, through a suitable adapter (not 50 shown), may be engaged with the boss 90 of the motor, thus placing the motor in circuit with the electrical conductors 103 and causing it to operate in a direction to wind up the cable on the drum and by so doing 55 lift the hoist to the desired elevation. The operator then engages the suspension hook 60 of the hoist with the clevis 127 of the trolley, or with any other support from which he desires to hang the hoist. When 65 this is done, he removes the adapter carried

by the switch member 112 from the boss 90 and inserts the plug 96, at the same time snapping the brake control cord or cable 88 to the lever 81.

In the manually operated hoist, illustrated in Figs. 8 and 9, the drum is designated 130, and it is supported, through a ball bearing 131, from a frame 132 made up of two side members between which the ball supporting and retaining ring 131^a is 70 clamped. A shaft 133 is supported by the frame 132 and mounted thereon is a worm 134. The worm 134 is similar to the combined worm and worm gear 31, shown in the previously described embodiment, the 80 essential difference being that instead of a worm gear, a chain sprocket 135 is formed about the equator of the worm. A chain 136 is engaged over the sprocket 135 and hangs down on opposite sides of the drum. 85 By means of the chain the worm may be rotated to impart rotation to the drum 130.

The frame 132 incorporates casings 137 which enclose the threaded ends of the worm 134 and provide lubricant chambers. Packing rings 139 are interposed between the portions of the casings 137 which surround the openings through which the worm is engaged and adjacent smooth portions that are formed on the worm, thereby to prevent 95 egress of the lubricant and ingress of dust or grit. The two halves of the frame 132 are connected together by bolts 140, the one occurring at the top of the frame serving as a means for connecting a yoke 141 to the 100 frame. A suspension hook 142 is swiveled to the yoke. To another of the bolts 140 is connected a loop 143 through which a hook 144, connected to one end of the cable 145, is engaged. The other end of the cable is 105 fastened to the drum, as indicated at 146. It is evident that the present modification is susceptible to the same sheave block and cable arrangements as were mentioned in connection with the former embodiment. 110

Having thus described my invention, what I claim is:

1. In combination, a drum, an internal worm gear carried by the drum, a worm meshing with the worm gear, and means for 115 driving the worm.

2. In combination, a drum, an internal worm gear carried by the drum, a worm meshing with the worm gear, and driving mechanism inside the drum and having operative connection with the worm. 120

3. In combination, a supporting structure, a drum rotatably supported thereby, an internal worm gear carried by the drum, a worm rotatably sustained by the structure in 125 mesh with the worm gear, and means for driving the worm.

4. In combination, a supporting structure, a drum rotatably supported thereby, an internal worm gear carried by the drum, a 130

worm rotatably sustained by the structure in mesh with the worm gear, and driving mechanism carried by the structure and having operative connection with the worm.

5 5. In combination, a supporting structure, a drum rotatably supported thereby, an internal worm gear carried by the drum; a worm rotatably sustained by the structure in mesh with the worm gear, said worm in-
10 corporating a circumferential gear, and means for rotating the latter gear.

15 6. In combination, a supporting structure, a drum rotatably supported thereby, an internal worm gear carried by the drum, a worm rotatably sustained by the structure in mesh with the worm gear, said worm having a worm gear about its equator, and driving mechanism sustained by the structure and incorporating a worm meshing
20 with the equatorial worm gear.

7. In combination, a drum, a supporting structure having bearings spaced apart axially of the drum and through which said drum is rotatably supported by the structure, an internal worm gear extending about the interior of the drum, a worm meshing with the worm gear, and means for rotating the worm.

8. In combination, a drum, a supporting structure having bearings spaced apart axially of the drum and by which said drum is rotatably supported, an internal worm gear extending about the interior of the drum, a worm sustained by the supporting structure in mesh with the worm gear, driving mechanism supported by said structure, and operative connections between said driving mechanism and the worm.

9. In combination, a drum, a supporting structure having bearings spaced apart axially of the drum and by which said drum is rotatably supported, an internal worm gear extending about the interior of the drum, a worm supported by the structure in mesh with the worm gear, said worm incorporating a circumferential gear, driving mechanism carried by the structure, and driving connections between said mechanism and said circumferential gear.

50 10. In combination, a drum, a supporting structure having bearings spaced apart axially of the drum and by which said drum is rotatably supported, an internal worm gear extending about the interior of the
55 drum, a worm rotatably supported by the structure in mesh with the internal worm gear, said worm having a worm gear extending about its equator, and driving mechanism carried by the structure and incorporating a worm meshing with the equatorial worm gear.

11. In a hoist of the class set forth, the combination of a motor, a drum surrounding the motor and rotatably supported thereby, an internal worm gear extending about the

interior of the drum, and a worm driven by the motor and meshing with the worm gear.

12. In a hoist of the class set forth, the combination of a motor involving a casing, a drum surrounding the motor casing, said casing having bearing portions in parallel planes spaced apart axially of the drum and whereon said drum is rotatably supported, an internal worm gear surrounding the interior of the drum, a worm supported by the casing in mesh with the internal worm gear, said worm having a worm gear extending about its equator, and a worm on the motor shaft meshing with the equatorial worm gear.

13. In a hoist of the class set forth, the combination of a motor involving a casing, a drum surrounding the motor casing, said casing having bearing portions in parallel planes spaced apart axially of the drum and whereon said drum is rotatably supported, an internal worm gear surrounding the interior of the drum, a worm supported by the casing in mesh with the internal worm gear, said worm having a worm gear extending about its equator, a worm on the motor shaft meshing with the equatorial worm gear, a brake drum carried by the rotating element of the motor, a brake member supported in operative relation thereto, and means for actuating the brake member.

14. In a hoist of the class set forth, the combination of an electric motor of the induction type having a so-called "squirrel cage" rotor winding in which one of the end rings is constituted of a cylindrical member serving as a brake drum, the motor involving a casing, a drum surrounding the motor casing, the casing having bearing portions in parallel planes spaced apart axially of the drum and through which the drum is rotatably supported, an internal worm gear extending about the interior of the drum, a worm rotatably supported by and within the motor casing in mesh with the internal worm gear, said worm incorporating a circumferential gear, and driving connections between said circumferential gear and the rotating element of the motor, a brake shoe supported by the motor casing in operative relation to the aforesaid brake drum, and means exterior of the motor casing for actuating said brake shoe.

15. In a hoist of the class set forth, the combination of an electric motor involving a casing, a drum surrounding the motor casing, anti-friction bearings through which the drum is rotatably supported upon the motor casing, an internal worm gear extending about the interior of the drum, a worm meshing with the worm gear, and driving connections between the motor shaft and said worm.

16. In a hoist of the class set forth, the combination of an electric motor involving 130

- a casing, a drum surrounding the motor casing, anti-friction bearings extending about the exterior of the motor casing, a worm gear extending about the interior of the drum, a worm enclosed and supported by the motor casing and meshing with the internal worm gear, said worm having a worm gear extending about its equator, the axis of the motor being inclined to the plane of the internal worm gear thereby to dispose one end of its shaft alongside said worm, and a worm mounted upon said end of the motor shaft for cooperation with the equatorial worm gear.
17. In a hoist of the class set forth, the combination of an electric motor involving a casing, a drum surrounding the motor casing, ball races extending about the motor casing and spaced apart axially of the drum, ball races fitted to the drum in opposed relation to the former ball races, balls interposed between the opposed ball races, an internal worm gear extending about the interior of the drum, a worm enclosed and supported by the motor casing and meshing with the internal worm gear, said worm having a worm gear extending about its equator, the axis of the motor being inclined to the plane of the internal worm gear thereby to dispose one end of its shaft alongside said worm, and a worm mounted upon said end of the motor shaft for cooperation with the equatorial worm gear.
18. In a hoist of the class set forth, the combination of an electric motor involving a substantially spherical casing, a drum surrounding the motor casing, the motor casing having annular shoulders in parallel planes spaced apart axially of the drum, ball races mounted upon said shoulders, ball races carried by the drum in opposed relation to the former ball races, balls interposed between the opposed races, an internal worm gear extending about the interior of the drum, a worm enclosed and supported by the motor casing in mesh with the internal worm gear, said worm having a worm gear extending about its equator, the axis of the motor being inclined to the plane of the internal worm gear so as to dispose one of its ends alongside said worm, and a worm mounted upon said end of the motor shaft and meshing with the equatorial worm gear.
19. In a hoist of the class set forth, the combination of an electric motor involving a casing, a drum surrounding the motor casing, bearings extending about the exterior of the motor casing and spaced apart axially of the drum and through which the drum is rotatably supported, an internal worm gear extending about the interior of the drum, a worm within and supported by the motor casing and meshing with the internal worm gear, one end of the motor shaft being disposed alongside the worm, driving connections between said end of the motor shaft and the worm, and a partition dividing the motor casing into a lubricant containing compartment, enclosing said worm and the driving connection between it and the motor shaft, and a second compartment enclosing the electrical elements of the motor, said partition having an aperture through which the motor shaft extends.
20. In a hoist of the class set forth, the combination of an electric motor involving a casing, a drum surrounding the motor casing, bearings extending about the exterior of the motor casing and spaced apart axially of the drum and through which the drum is rotatably supported, an internal worm gear extending about the interior of the drum, a worm within and supported by the motor casing and meshing with the internal worm gear, one end of the motor shaft being disposed alongside the worm, driving connections between said end of the motor shaft and the worm, a partition dividing the motor casing into a lubricant containing compartment, enclosing said worm and the driving connection between it and the motor shaft, and a second compartment enclosing the electrical elements of the motor, said partition having an aperture through which the motor shaft extends, and a guard surrounding said aperture to prevent passage of lubricant from the first to the second of said compartments.
21. In a hoist of the class set forth, the combination of an electric motor involving a casing, a drum surrounding the motor casing, bearings extending about the exterior of the motor casing and spaced apart axially of the drum and by which the drum is rotatably supported, an internal worm gear surrounding the interior of the drum, a worm within and supported by the motor casing and meshing with the internal worm gear, one end of the motor shaft being disposed alongside the worm, driving connections between said end of the motor shaft and the worm, a partition dividing the motor casing into a lubricant containing compartment, enclosing said worm and the driving connection between it and the motor shaft, and a second compartment enclosing the electrical elements of the motor, said partition having an aperture through which the motor shaft extends, and a guard surrounding said aperture to prevent passage of lubricant from the first to the second of said compartments, a brake member carried by the rotating element of the motor, a second brake member carried by said partition for cooperation with the first mentioned brake member, and means exterior of the casing for actuating the second brake member.
22. In a hoist of the class set forth, the

ing disposed alongside the worm, driving connections between said end of the motor shaft and the worm, and a partition dividing the motor casing into a lubricant containing compartment, enclosing said worm and the driving connection between it and the motor shaft, and a second compartment enclosing the electrical elements of the motor, said partition having an aperture through which the motor shaft extends.

20. In a hoist of the class set forth, the combination of an electric motor involving a casing, a drum surrounding the motor casing, bearings extending about the exterior of the motor casing and spaced apart axially of the drum and through which the drum is rotatably supported, an internal worm gear extending about the interior of the drum, a worm within and supported by the motor casing and meshing with the internal worm gear, one end of the motor shaft being disposed alongside the worm, driving connections between said end of the motor shaft and the worm, a partition dividing the motor casing into a lubricant containing compartment, enclosing said worm and the driving connection between it and the motor shaft, and a second compartment enclosing the electrical elements of the motor, said partition having an aperture through which the motor shaft extends, and a guard surrounding said aperture to prevent passage of lubricant from the first to the second of said compartments.

21. In a hoist of the class set forth, the combination of an electric motor involving a casing, a drum surrounding the motor casing, bearings extending about the exterior of the motor casing and spaced apart axially of the drum and by which the drum is rotatably supported, an internal worm gear surrounding the interior of the drum, a worm within and supported by the motor casing and meshing with the internal worm gear, one end of the motor shaft being disposed alongside the worm, driving connections between said end of the motor shaft and the worm, a partition dividing the motor casing into a lubricant containing compartment, enclosing said worm and the driving connection between it and the motor shaft, and a second compartment enclosing the electrical elements of the motor, said partition having an aperture through which the motor shaft extends, and a guard surrounding said aperture to prevent passage of lubricant from the first to the second of said compartments, a brake member carried by the rotating element of the motor, a second brake member carried by said partition for cooperation with the first mentioned brake member, and means exterior of the casing for actuating the second brake member.

combination with a supporting structure, a drum rotatably supported thereby, an electric motor carried by the structure, brake mechanism for controlling the motor, and a control element including electrical conductors and a switch through which current is supplied to the motor, said element hav-

ing connection with the aforesaid brake whereby said brake may be actuated by the control element. 10

In testimony whereof, I hereunto affix my signature.

THOMAS E. ADAMS.
